GAME

Francisco Feitosa, New York, N. Y.

Application May 24, 1935, Serial No. 23,321

3 Claims. (Cl. 273—97)

This invention relates to improvements in games, and has specific relation to games of skill.

It is an object of this invention to provide a new game which will not only afford amusement and entertainment to the player, but will give both mental and physical exercise and will serve to coordinate the action of the eye and body muscles.

In the accompanying drawing:

10 Fig. 1 is a perspective view of my game with a portion of the flexible connection between the operating member and target member omitted;

Fig. 2 is a sectional view of the target member on the line 2—2 of Fig. 1;

15 Fig. 3 is a plan view of the target member; and

Fig. 4 is a perspective view of a modified form of target member.

My improved game includes an operating member 10, a target member 11, and a flexible connection such as the cord 12 secured at its two ends to the target and operating member, respectively. The operating member 10 preferably comprises a handle 13 to which the cord 12 is secured, a tapering stud 14 preferably formed integral with the handle, and a guard plate 15 formed with a central opening 16 through which the stud 14 projects. The guard plate is formed with a plurality of sections 17, preferably colored red and blue alternately, on its upper face on which suitable indicia, such as the numerals 18, are provided, and it is formed with a plurality of sides, one for each of the sections formed on the face of the plate.

The target 11 is preferably in the form of an elongated multi-sided hollow member having a top 19, sides 20 and bottom 21. The top and sides are preferably formed of a relatively light strong material, such as a heavy cardboard or similar fibrous material, while the bottom 21 should be made of relatively strong materials, such as wood. The sides 20 are preferably alternately colored red and blue and provided with suitable indicia, such as the numerals 22.

A plurality of openings 23 are formed adjacent the periphery of the bottom 21, one opening being formed near the lower end of each of the sides and an opening 24 is formed at approximately the center of the bottom. Each of the openings should be of sufficient size to receive the stud 14. To give additional strength to the target member, a tubular support 25 is preferably disposed between the top and bottom in the inside of the target and may be suitably supported as by the cylindrical flange 26 secured to the top, and by the screws 27 anchored in the bottom 21 of the

target and extending through the braces 28 and disk 29 secured to or formed integral with the tubular support.

The top of the target is preferably divided into a plurality of sections 30 which preferably are alternately colored red and blue to correspond with the colors on the sides of the target. To secure the cord 12 to the upper end of the target, an opening 31 is provided through which the knotted end of the cord 32 extends.

10 In the form of my target shown in Fig. 4, a plurality of rectangular projections 33 are formed around the sides of the target and the indicia or numerals 22 are applied to the outer face of the projections. These projections likewise are 15 preferably colored red and blue alternately. The openings 23 formed in the bottom of the target are disposed at the lower end of each of the cylindrical projections.

10 In playing my improved game, the player grasps 20 the handle 13 of the operating member and permits the target to hang freely a short distance above the ground. He then endeavors to swing the target upwardly, by manipulating the operating member, to a position where he can project 25 the stud 14 into one of the openings 23 or 24 formed in the bottom of the target.

The score may be computed in any desired manner, such as allowing a score of one when the stud 14 enters the central opening 24, and where 30 the stud enters one of the openings 23 around the periphery of the bottom of the target, allowing a score equivalent to the sum or product of the numeral appearing on the adjacent side of the target and the numeral appearing on the proximate section of the guard plate 17. Variations in 35 scoring may be made, such as deducting the sum or product computed as aforesaid from the score where the color on the side of the target does not correspond to the color on the proximate section 40 of the guard plate, and awarding the sum or product to the player where the colors do correspond.

Of course, it is to be understood that many 45 modifications may be made in the form, color or shape of the operating member and target member without departing from the invention herein described and illustrated.

I claim:

1. A game of the character described comprising 50 an operating member including a handle, a guard plate having indicia thereon secured to said handle and a tapering stud projecting from the top of said guard plate; a target including an 55

elongated member having a plurality of sides with indicia thereon and a plurality of openings of a size to receive said stud formed in its lower end, one opening being disposed adjacent each of said sides; and a flexible connection between the central portion of the upper end of said target and said operating member.

2. A game of the character described comprising an operating member including a handle, a 10 guard plate divided into a plurality of fields having distinguishing indicia thereon secured to said handle, and a tapering stud projecting from the top of said guard plate; a target including an elongated member having a top, a bottom and a 15 plurality of projecting sides, said sides being provided with distinguishing indicia and said bottom with a plurality of openings of a size to receive said stud, one opening being disposed adjacent each of said sides; and a flexible connection be-

tween the central portion of the upper end of said target and said operating member.

3. A game of the character described comprised of a target formed of an elongated member having a plurality of openings in its lower end and distinguishing indicia for each of said openings, a flexible cord connected adjacent one end to approximately the center of the top of the target, and an operating member connected to the other end of the flexible cord and including a handle 10 to be gripped by the player to manipulate the target, a guard member having distinguishing indicia thereon, and a lug projecting from adjacent the central portion of said guard member, said lug being so positioned and being of such a 15 size that it may be projected into one of the openings in the target when the target has been manipulated to the proper position.

FRANCISCO FEITOSA.
